UNITED STATES PATENT OFFICE.

GEORGE M. TAGGART, JR., AND FRANK M. NICHOLS, OF SEATTLE, WASHINGTON.

HAIRPIN.

Application filed November 16, 1925. Serial No. 69,342.

Our invention relates to improvements in hairpins of the form disclosed but not claimed in our prior Patent No. 1,528,454 issued March 3, 1925.

5 The object of our invention is to provide a hairpin designed particularly for use with short or bobbed hair, wherein through the particular formation of the hairpin an unusual frictional grip is secured upon the 10 hair, with the result of effectively holding the folds or coils of the hair notwithstanding its short length.

Our improved hairpin comprises a length 15 of resilient material of greater width than thickness, bent to provide an open loop at one end and having legs with broad flat surfaces in contact throughout their length, said legs being bent sinuously so that the pin has a wave like appearance and the ends 20 of the legs being slightly out-turned or flared to facilitate insertion of the hair.

The invention is illustrated in the accompanying drawings, wherein—

Figure 1 is an edge view of our hairpin; 25 and

Fig. 2 is a side view of the same.

Referring to the drawings, throughout 30 which like reference numerals indicate like parts, this hairpin comprises a piece of resilient material bent double to form an end loop 3 and two legs 4 and 5 projecting from the loop and substantially in contact throughout their full lengths. The outer 35 ends of the legs 4 and 5 are slightly out-turned as at 6 to facilitate spreading the same apart in the application of the hairpin. The legs are bent sinuously to give the pin a wave like appearance and to cause the

same to hold the hair more tightly. The sinuous bending of the legs 4 and 5 make it 40 difficult to conceal this hairpin in the hair, consequently this hairpin is of the visible rather than the invisible type. The convex portions of said legs 4 and 5 are especially well adapted to receive ornamentation of 45 any suitable form as indicated at 7.

The hair pin is constructed of material having a greater width than thickness and the material is bent crosswise so that the broad flat surfaces of the same are in contact with each other.

The important feature of this invention is the provision of the resilient sinuous legs having comparatively broad bearing surfaces so as to form an effective grip or frictional contact with the hair so that the hair may be retained in position notwithstanding its comparatively short length.

The foregoing description and accompanying drawings clearly disclose a preferred embodiment of our invention but it will be understood that numerous changes in the same may be resorted to within the scope of the following claim.

What we claim is:

65 A hair pin constructed of spring material having a materially greater width than thickness, said material being formed into a hairpin providing a loop at one end, and sinuous legs beyond the loop disposed with 70 their broad surfaces in contact.

In witness whereof, we hereunto subscribe our names this 25th day of January, A. D. 1926.

GEORGE M. TAGGART, JR.
FRANK M. NICHOLS.
